UNITED STATES PATENT OFFICE.

CORNELIUS S. CLARK, OF NORFOLK, VIRGINIA.

INTERNAL-COMBUSTION ENGINE.

Application filed May 3, 1924. Serial No. 710,882.

To all whom it may concern:

Be it known that I, CORNELIUS S. CLARK, a citizen of the United States, residing at Norfolk, in the county of Norfolk and State of Virginia, have invented new and useful Improvements in Internal-Combustion Engines, of which the following is a specification.

This invention relates to internal combustion engines and proposes the construction of means whereby the co-acting walls of cylinder and piston are relieved of surplus leakage products in the respective forms of gasoline, which may be forced past the piston rings upon the compression and explosion strokes of the engine, and lubricating oil which may be drawn up from the crank case upon the suction stroke.

The invention has for its objects the conservation of fuel and the preservation of the lubricating oil by segregating these surplus leakage products, returning the gasoline directly to the combustible mixture supply, and the lubricating oil to the crank case.

25 A further object of the invention is the utilization of the vacuum produced by the functioning of the engine, for inducing the return of said segregated products.

In the drawings:—

30 Figure 1 represents a side elevation of a multi-cylinder internal combustion engine having my invention applied thereto.

Figures 2 and 3 represent longitudinal sections of one of the cylinders of the engine shown in Figure 1 with the pistons at the opposite limits of travel.

Referring now in detail to the several figures, the numeral 1 represents a cylinder block supported upon the crank case 2. The cylinders 3 are supplied with combustible mixture by means of a manifold 4 connected to a carburetor 5. Pistons 6 travel in the cylinders.

45 None of the features enumerated, in the above paragraph are unusual, except that for the purpose of efficiently carrying out my invention the pistons are provided with rings 7 at each end. These rings are for the purpose of sealing the combustion chamber and also the space within the crank case below said pistons from the vacuum which is applied to the portion of the piston and cylinder walls intermediate the piston rings.

50 It is well known that a portion of the liquid fuel now available for use in internal combustion engines is not volatile at low en-

gine temperatures and that it either remains in liquid form or is condensed into a liquid after reaching the engine cylinders. Such liquid, or a portion thereof is then forced 60 down below the piston rings upon the compression and explosion strokes of the engine and finds its way into the crank case. Here it commingles with the lubricating oil, impairing the viscosity of the latter and 65 rendering it unfit for use in a short while so that it is necessary frequently to drain the crank case and throw away the spent oil. This amounts to a waste of fuel as well as lubricating oil, both of which are conserved 70 by the application of my invention.

In carrying out the principles of the present invention, I provide the cylinder wall with an upper annular channel 8 extending thereabout, said channel being located at 75 such point in the cylinder as will be traversed by the intermediate portion of the piston body but never transected by the piston rings. Said channel is connected with a conduit 9, the latter being one of the 80 branches leading to a manifold 10, communicating with the intake manifold 4 by means of a conduit 11.

A lower channel 12 is provided at an appropriate distance beneath the channel 8 85 which lower channel is also within the range of movement of the intermediate portion of the piston. The channel 12 is connected by a conduit 13 with a manifold 14 which leads to the upper portion of a vacuum tank 15. 90 Nothing novel is claimed for this vacuum tank per se, it being preferably the same vacuum tank as is generally used for elevating fuel from a lower supply tank to a carburetor. The vacuum chamber of the 95 vacuum tank is connected to the intake manifold by means of the pipe 16 and the discharge pipe 17 of the vacuum tank enters at an appropriate point into the crank case.

In the operation of my invention a charge 100 of fuel mixture is exploded in the cylinder 3 when the piston is at the top of its stroke as shown in Figure 3, said explosion forcing either liquid or vaporized fuel past the upper piston ring 7 and into the annular space between the cylinder and piston walls and intermediate the piston rings. This fuel is trapped in the upper channel 8 and carried by suction directly into the intake manifold 4 where it forms a proportion of the fuel 105 being drawn into the cylinder and consumed in the succeeding explosion. This salved

fuel enriches the mixture to such an extent that the carburetor may be adjusted to supply a leaner mixture and a considerable saving in fuel effected.

5 When the piston descends upon the suction stroke a high degree of vacuum is engendered within the combustion space prior to the admission of a new charge of mixture, which vacuum causes the drawing up 10 of a quantity of oil from those surfaces below the piston which have been lubricated by splash from the crank case. Said oil is entrapped in the lower channel 12 and carried by suction to the vacuum tank 15, 15 whence it flows into the crank case. In devices that have hitherto been proposed for the conservation of the lubricating oil by collecting the surplus leakage products no attempt has been made to segregate the gaso- 20 line and lubricating oil so that there would be no mixing of the same. In fact, inventive endeavor along this line has been di- rected to the purging of the cylinder walls of excess lubricating oil to prevent carboni- 25 zation of the cylinders and pistons rather than to conserve the lubricating oil in the crank case. In those pistons of which I am aware, where it has been attempted to draw away the surplus oil and gasoline from be- 30 tween the piston and cylinder walls, the re- sulting product has been invariably re- turned to the engine crank case.

It is also an established fact that when gasoline or the heavier fractions of the liquid 35 fuel have once mixed with lubricating oil it is a practical impossibility to separate them by any known process short of actual distillation. By the present invention, how- ever, the gasoline and lubricating oil are 40 never permitted to mix, being segregated by the upper and lower annular channels. It would of course be possible to return the fuel constituent to the fuel supply tank (not shown) if desired, but as the quantity of 45 liquid fuel conserved at each explosion is relatively small it has been found very practical to return it direct to the intake mani- fold. In the case of the lubricating oil it has been found necessary to use a vacuum 50 tank or like device, for, on account of the absence of suction in the crank case it would be impracticable to make a direct connection between the lower channel and the crank case.

55 Although I have thus described the preferred embodiment of my invention, it is evident that those skilled in the art to which this relates may make various changes in the construction, combination and arrange- 60 ment of the several parts without departing from the spirit and scope of the invention.

Having described my invention what I claim as new and desire to secure by Letters Patent, is:-

65 1. In an internal combustion engine, a

cylinder including a combustion chamber, and a crank case, a piston in said cylinder reciprocable relative thereto and separating that portion of the cylinder wall exposed to the combustion chamber from that part 70 exposed to the crank case, one of said relatively reciprocable members being provided with means constantly overlain by the other for entrapping fuel leaking from the combustion chamber past the piston, and 75 with separate means for intercepting the lub- ricaning oil leaking past said piston from the crank case whereby said leaking sub- stances are segregated, and means for return- ing said substances to the parts of the engine 80 from which they emanated.

2. In an internal combustion engine, a cylinder including a combustion chamber, and a crank case, a piston in said cylinder reciprocable relative thereto and separating 85 that portion of the cylinder wall exposed to the combustion chamber from that part ex- posed to the crank case, one of said relatively reciprocable members being provided with means constantly overlain by the other for entrapping fuel leaking from the combus- tion chamber past said piston, and with 90 separate means for intercepting lubricating oil leaking past said piston from the crank case, whereby said leaking substances are 95 segregated, and means operating through suction of the engine for returning said en- trapped fuel to the fuel mixture intake of the engine, and said lubricating oil to the crank 100 case.

3. In an internal combustion engine, a cylinder including a combustion chamber, and a crank case, a piston in said cylinder reciprocable relative thereto and separating 105 that portion of the cylinder wall exposed to the combustion chamber from that part ex- posed to the crank case, one of said relatively reciprocable members being provided with upper and lower annular channels extending 110 transversely thereabout and constantly overlain by the other of said reciprocable mem- bers, the upper channel functioning to entrap fuel leaking from the combustion chamber past said piston and the lower channel being designed to intercept lubricating oil leaking 115 past the piston from the crank case, whereby said leaking substances are segregated, a con- duct connecting said upper channel with the fuel intake of the engine, a vacuum tank also connected to said fuel intake, a conduit lead- ing from the lower channel to said vacuum tank and a discharge conduit extending from said vacuum tank to the crank case of the engine. 120

4. In an internal combustion engine, a cylinder including a combustion chamber, and a crank case, a piston in said cylinder reciprocable relative thereto and separating 125 that portion of the cylinder wall exposed to the combustion chamber from that part

exposed to the crank case, said cylinder being provided with upper and lower annular channels extending transversely thereabout, said upper channel functioning to entrap fuel leaking from the combustion chamber past the piston and said lower channel intercepting lubricating oil leaking past said piston from the crank case, whereby said leaking substances are segregated, a conduit connecting said upper annular channel with the fuel mixture intake pipe of the engine, a vacuum tank also connected to said fuel mixture intake, a conduit connecting said lower channel with said vacuum tank and a discharge conduit leading from said vacuum tank to the crank case of the engine.

5. In an internal combustion engine, a cylinder including a combustion chamber, and a crank case, a piston in said cylinder reciprocable relative thereto and separating that portion of the cylinder wall exposed to the combustion chamber from that part exposed to the crank case, one of said relatively reciprocable members being provided with means constantly overlain by the other for entrapping fuel leaking from the combustion chamber past the piston, and with separate means for intercepting the lubricating oil leaking past said piston from the crank case, whereby said leaking substances are segregated, and means for returning said substances to the engine.

In testimony whereof I have hereunto set my hand.

CORNELIUS S. CLARK.
